RECOILLESS GUN

Latham Valentine Stewart Blacker, Fittleworth,
Pulborough, EnglandApplication September 19, 1944, Serial No. 554,820
In Great Britain May 4, 1938

11 Claims. (Cl. 89—1.7)

1

This invention relates to recoilless guns.

An important object of my invention is to provide a gun in which the recoil forces generated upon the discharge of a propellant cartridge are largely absorbed and are utilized for recocking the gun.

Another object of my invention is to provide means for accurately locating a projectile in position in a gun so that a moving striker can enter a narrow tube in the tail of the projectile and discharge a propellant charge at the end of the tube.

A further object of my invention is to provide an improved form of trigger and automatic cocking mechanism.

Yet another object of my invention is to provide an improved gun with a magazine for projectiles and with means by which the feed to the magazine and the recocking are wholly automatic.

Further objects of my invention will appear in the course of the following description when read in conjunction with the annexed drawings, in which:

Figure 1 is a central longitudinal section through one form of gun with the parts in the cocked position;

Figure 2 is a plan of the Figure 1 gun;

Figure 3 is a section similar to Figure 1 at the moment of discharge of the cartridge;

Figure 3a is a longitudinal sectional view of a projectile with a fragmentary showing of the striker;

Figure 4 is a longitudinal section through a modified form of trigger mechanism suitable for use in a gun of the kind shown in Figures 1 to 3;

Figure 5 is a central longitudinal section through a larger gun mounted in a tank;

Figure 6 is a section through the trigger mechanism of the gun shown in Figure 5;

Figure 7 is a side view of a magazine gun;

Figure 8 is a longitudinal horizontal section through the gun shown in Figure 7, with the parts in the cocked position;

Figure 9 is a section similar to Figure 8 at the moment of discharge of the propellant cartridge; and

Figure 10 is a section on the line X—X in Figure 7.

The gun shown in Figures 1 to 3 comprises a cylindrical casing 1 which carries at its forward end a cap 2 around which a ring 3 is fixed. The gun is designed to project a projectile 4, and an open-topped loading trough 5 for the projectile 4 has a cylindrical rearward end 6 which fits over

2

the ring 3. The projectile has a tube 7 located partly inside and partly outside its tail end and carrying a drum tail 8, and a cartridge 9 is provided at the inner end of the tail tube 7. In order to project the projectile it is necessary to discharge this cartridge 9 and for this purpose a movable striker 10 is arranged to fly forward into and through the tail tube 7. The nose of the striker forms a firing pin which, on reaching the cartridge, enters the primer 9b of the cartridge 9, striker 10 thereby serving as a firing pin carrier. The forward portion of the projectile 4 will include a grenade or the like 4a.

The striker 10 forms part of a heavy dynamic mass, the momentum of which is utilized to absorb a substantial part of the recoil forces generated on discharge of the propellant cartridge 9. This dynamic mass largely consists of a heavy sleeve 11 the bore of which is reduced in diameter and internally screw-threaded to receive the threaded end 12 of the striker 10, which has a flange 13 which abuts against the shoulder formed by the reduced part of the bore in sleeve 11. A piston-like head or disc 14 constituting a cocking shoulder is screwed on to the sleeve 11. Head 14 also forms part of the above-mentioned dynamic mass. The sleeve 11 can slide within a cocking tube 16 which is welded to a back plate or butt 17. An outer cup 18 is also welded to the back plate and surrounds an inner cup 19 which is welded to the casing 1. A spring 20 surrounds the cocking tube 16, bearing at one end on the inner cup 19 and at the other end on the piston-like head 14, and being surrounded by a skirt 15 which extends rearwardly from the disc 14 and guides and steadies the spring in operation.

In the cocked position shown in Figure 1 the dynamic mass including striker 10, sleeve 11 and skirted disc 14 is held against the action of the spring 20 by a control mechanism comprising a sear 21 which engages the forward edge of the disc 14 and is pivotally mounted on a pin 28 which is fixed in a housing 23. This sear is urged into the latching position by a compression spring 22 also mounted within housing 23. The trigger 24 is pivotally mounted on a pin 25 extending across the housing 23, and the finger piece of the trigger projects through an opening 123 in the housing 23. The trigger is connected by a pivot pin 124 to a disconnector 26, the forward end of which bears on a nose 27 formed on the sear 21. When the trigger 24 is pressed the disconnector 26 rocks the sear 21 so that the dynamic mass is released and driven rapidly forward by the spring 20 into the position shown in Figure 3. The

striker 10 traveling up the tail tube 7 of the projectile to discharge the cartridge 9 so that the projectile is projected. On the discharge of the cartridge 9 its rear portion 9a is driven backwards into the tail tube 7 and seals the explosion gases. It is important that on discharge the rear part of the cartridge should expand radially and completely obturate the tail tube. This part 9a of the cartridge acts as a piston which bears directly on the striker 10, driving the dynamic mass backwards. In this manner, not only are the recoil forces absorbed but they are directly and consistently applied to the dynamic mass to bring about automatic recocking.

For recocking purposes it is essential that the sear 21 should be allowed to return to the cocking position freely and immediately. As this might be prevented if the nose of the disconnector 26 could remain in engagement with the nose 27 of the sear, a fixed pin 29 is provided to cooperate with a sloping surface on the disconnector so that as the trigger 24 is pressed completely backwards the disconnector after rocking the sear is forced downwards away from the nose 27. If the trigger 24 remains pressed during the whole of the recoil of the dynamic mass the sear 21 will act independently of the trigger and disconnector and latch the disc 14 in the cocked position shown in Figure 1 when the dynamic mass recoils under the action of the recoil forces. If the trigger be released before the dynamic mass returns, the disconnector 26 will be moved outwards by the engagement of the rearward edge of the disc 14 with a forked nose 30, the two arms of which are rigid with the disconnector and lie one on each side of the sear 21. Immediately disc 14 has passed over this nose the disconnector and trigger will be returned to the ready-to-fire position by means of a spring 31 anchored at one end to the disconnector and at the other end to the casing 1. In the absence of the forked nose 30 the user of the weapon, by releasing the trigger during the movement of the dynamic mass, might cause the nose of the disconnector to re-engage with the sear 21 prematurely.

A hand grip 32 and a trigger guard 33 of the usual kind are provided, as also are a foresight 34 on the loading trough 5 and a backsight 35 on the casing 1.

It is of course necessary to be able to cock the gun initially even though it is self-cocking whenever it is fired. For this purpose the assembly formed by the back plate 17, outer cup 18 and cocking tube element 16 is made disconnectible, the outer cup 18 being formed with two bayonet slots 36 entered by studs 37 carried by the inner cup 19. When the gun is to be cocked initially the back plate assembly is turned through 90° so that it is unlocked as a whole and can slide rearwardly relatively to the studs 37. The back plate assembly is then pulled back, and this results in an inner flange 38 at the end of the cocking tube coming into contact with a flange 39 at the end of the sleeve 11 so that the latter is pulled backwards against the spring 20 until the head 14 engages the sear 21 and the dynamic mass is cocked, i. e., held by sear 21. The back plate assembly is thereafter free to be pushed home and relocked by rotation through 90° when the locking studs 37 have entered the slots 36.

It will be observed that the sleeve 11 is hollow, and accordingly in the forward movement can pass over a guide tube 40 which projects rearwardly from the end cap 2 and serves to guide the striker 10. This telescoping of the sleeve 11

and the guide tube allows of a very long recoiling movement in relation to the overall dimensions of the weapon and so allows the recoil forces to be absorbed relatively gradually.

When the striker 10 travels rapidly up the tail tube 7 of the projectile, air is compressed in the tail tube with the result that there is an immediate force exerted on the projectile before the propellant cartridge is discharged. If the projectile were simply placed in the loading trough without being restrained in any way it might move forward under the action of this force and the striker might then fail to discharge the cartridge. To prevent this the projectile is provided with a collar 41 which is united to the end of the tail tube by means of a light soldered joint or equivalent connection which will easily break or shear or pull off when the propellant cartridge 9 is discharged. This collar 41 engages behind ribs 42 which are made rigid with the cap 2 and this engagement serves to hold the projectile in position until the cartridge is discharged.

It is desirable that the projectile should be loaded transversely rather than axially, since in this way the risk of the loader placing his hand in the path of the striker and so being injured if the weapon is accidentally fired is minimised. With transverse loading the striker must have a long enough recoil movement to be clear of the loading trough in the cocked position, so means must be provided for locating the projectile accurately in position relatively to the striker and the guide tube 40. Registration in a vertical direction is ensured because the drum 8 of the projectile rests on the bottom of the loading trough 5, but naturally to enable projectiles to be loaded quickly there must be a relatively large clearance between the walls of the trough and the projectiles. The ribs 42 serve the useful additional function of guiding the tail end of the projectile during the loading and locating the tail tube laterally in exact register with the end of the guide tube 40.

When the cartridge has been discharged and the connections between the collar 41 and the end of the tail tube 7 is broken the collar 41 falls out of the loading trough through an opening 43, as also does the rear portion of the fired cartridge.

Figure 4 shows a modified control mechanism. In this case a disconnector in tension is used and is shown at 44. It has a hooked part 45 which engages behind a nose on a sear 21', which is subjected to the action of a spring 22' and is pivoted on a pin 28'. The disconnector, which has a hump 46 which is engaged by the disc 14 during cocking, is not directly pivoted to the trigger 24' but by a pin 144 to a lever 47 which is itself connected by a square pin 145 to the trigger and which also carries a pin 146 to which a spring 48 is anchored, the other end of the spring being anchored to the disconnector 44. It will be observed that whereas in the construction shown in Figure 1 the disconnector and sear are at the same point along the gun, in the modification shown in Figure 4 they are at different points so the disconnector does not have to be forked to embrace the sear. To fire the weapon with this modified trigger mechanism the trigger 24' is pulled, the action of the operator's finger causing the trigger to rock clockwise, the link 47 rocking clockwise with the trigger. As a result the disconnector 44 is pulled bodily towards the muzzle end of the gun and the hook 45 causes the sear 21' to rock anti-clockwise until the disc 14 is released. On the return movement the hump 46

is forced downwards until the disc 14 has passed over it, so that even if the trigger is released during the return of the dynamic mass the hook 45 will not re-engage the sear 21' prematurely.

The gun shown in Figure 5 is larger than that of Figures 1 to 3 and is intended to be mounted in a tank or other self-propelled vehicle. It is shown in position inside a tank, part of the armour of which is shown at 50. The gun as a whole is carried by a mantlet 51, which is mounted on trunnions 52 fixed inside the tank. The mantlet includes a support 53 to which an end cap 54 rigid with the casing 55 of the weapon is bolted. Fixed within the end cap 54 is a guide tube 56 which receives a large sliding member or bolt 57 from which the striker 58 projects forward. The sliding member 57 is secured to a skirt-like tube 59 which receives an actuating spring 60, the other end of which bears against a rear end cap 61. The tube 59, striker 58 and sliding member 57 form a large dynamic mass capable of absorbing the greater recoil forces generated upon the discharge of the larger projectile fired by this gun. At the forward end of the guide tube 56 there is a plate 62 to which a loading trough 63 is bolted and with which a guide tube 64 for the striker 58 is made rigid. The guide tube 56 passes through an opening 65 in the armour of the tank and protection against the passage of bullets through this opening is given by the mantlet 51.

The control mechanism is somewhat different in this gun and is shown in detail in Figure 6. There are two sears 66 and 67 which engage the forward end of the sliding member 57 in the cocked position. Both sears are in a dust-proof casing 173. The nose 73a of a disconnector 73 bears against the tail of the sear 67. This disconnector is pivotally connected by a pivot pin 179 (which extends across the casing 173) to an arm 180 which in turn is rigidly connected to a trigger 74 by a pin 181 which extends through the wall of the casing 173 and terminates outside the casing in a square end which engages a square hole in the trigger. The disconnector is subjected to the action of a tension spring 185 which is anchored at one end to the disconnector and at the other end to the tube 56 at 178. When the lower end of the trigger 74 is pulled back (to the left in Figure 6), the disconnector 73 is pushed forward, i. e., to the right, and its nose 73a pushes against the sear 67, causing the latter to rock anti-clockwise to move clear of 57. The sear 67 is connected rigidly to an arm 174 by the square end of a pin 175. Arm 174 is outside the casing 173 and is pivotally connected to a link 69 by a pin 169. As the arm 174 rocks with the sear, the link 69 is pulled and turns a crank wheel 70 to which it is connected by a pin 182. A second link 68 is pivoted to the crank wheel by a pin 183 and also to an arm 176 by a pin 184. This arm 176 is rigidly connected by the square end of a pin 177 to the sear 66. When the crank wheel 70 is turned by the pull on the link 69 the link 68 is pushed and rocks the arm 176 with the result that the sear 66 also moves clear of 57. The two sears are subjected to the action of springs 71 and 72, respectively. The springs are very diagrammatically shown as mounted in small housings. A pin 175 is provided for the same purpose as the pin 29 in Figure 1. During the recoil movement, the sliding member 57 bears on the disconnector 73 so that only when the member 57 has cleared the disconnector is it possible for the tail of the

disconnector once more to engage the tail of the sear 73.

The gun shown in Figures 5 and 6 is too large to be cocked by hand initially. Accordingly a 5 cocking winch 76 may be provided in the tank and when the gun is to be cocked a screw-threaded bar 77 carried on the end of a wire rope 78 attached to the winch is screwed into a threaded socket 79 formed in the end of the sliding 10 member 57. The whole sliding member and the parts associated with it are then pulled back into the cocked position by turning the handle 80 of the winch.

In the gun shown in Figures 7 to 10 there is a 15 heavy end plate 81 which carries a member 82 by which the whole gun may be pivotally secured to a base plate. In this case the dynamic mass is composed of a heavy sliding plate 83, a tube 84 closed by an end cap 85 from which a striker 86 projects forwardly and two tubes 87 fixed in the 20 plate 83. These tubes 87 slide over fixed tubes 88 which surround fixed rods 89. Two actuating springs 90 are provided, each surrounding one of the rods 89 within the corresponding tube 90 and bearing at its forward end on the closed forward 25 end of the corresponding tube 87.

This gun is of the magazine type and it includes a trough 91 into which projectiles 92 are loaded so that they tend to move vertically downwards in the trough with their axes horizontal. 30 The trough 91 is carried by the rods 89 which project forwards through the ends of the tubes 87 and enter a support 93 which is also fixed to the base plate by means not shown. The lower-most projectile rests on the bottom of the trough 35 91 and the projectile next above it is held by two pairs of pivotally mounted feed pawls or jaws 94 and 95 and 96 and 97 respectively. The pawls 94 and 96 are keyed to a shaft 98 and the pawls 95 and 97 are keyed to a similar parallel shaft 99. 40 These shafts are mounted in brackets 110 carried by the trough 91. The pawls 94 and 95 are interconnected by a linkage comprising a connecting rod 100 and two arms 101 and 102, each connected at one end to the connecting rod 100. These arms 101 and 102 are respectively fixed to the shafts 98 and 99, so that when the one shaft rocks the other must rock in the opposite direction. There are two such linkages, one at each 45 end of the pair of shafts 98 and 99. The shaft 98 carries a cam 103 which lies in the path of a finger 104 pivotally mounted at 105 on an extension 106 of the tube 88. The finger 104 can rock anti-clockwise against a spring 107 but is prevented from moving in a clockwise direction beyond the position shown in Figure 7 by an abutment 108 on the extension 106. When the whole 50 dynamic mass moves forward the finger 104 strikes the rearward end of the cam 103 and rocks against the action of the spring 107 so that it is carried under the cam. Directly it clears the cam it is restored by the spring to the vertical position. On the return movement of the dynamic mass the back of the finger 104 bears on the inclined surface of the cam 103 and rocks it and the shaft 98 clockwise as seen in Figure 10. 55 In consequence the pawls 94 and 96 are rocked clockwise and the pawls 95 and 97 anti-clockwise and the projectile which they previously supported descends to the bottom of the trough 91. All these rocked parts are restored to their initial position by the action of springs 109 directly the bomb has moved downwards out of the jaws, so 60 that the next projectile is caught by and retained 65 in the jaws.

The rearward end of the trough 91 is provided with ribs 111 similar to the ribs 42 shown in Figures 1 to 3.

The trigger mechanism of the gun of Figures 7 to 10 is not shown and may work on the same principle as those shown in Figures 1, 3, 4 and 6.

I claim:

1. In combination, a projectile and gun, the projectile being provided with an axial bore open at its rearward end, a propellant cartridge positioned in the bore in advance of said rearward end, said cartridge including an obturator portion movable along said bore and arranged to form a gas seal therein, the gun including a casing, a heavy dynamic mass including a forwardly extending firing pin, means for driving said mass toward the forward end of said casing, sear means for holding said mass against the action of said driving means, trigger means to operate said sear means to release position, means to support the projectile with its propellant cartridge in the path of movement of said firing pin, said firing pin having sufficient length to extend into the projectile recess and detonate the propellant cartridge when said mass is moved forward, whereby detonation of said cartridge will drive said obturator portion of the projectile propellant cartridge rearwardly in the projectile bore and in gas-sealing relation to the bore to thereby move said mass rearwardly with respect to said casing, said mass and driving means therefor being sufficiently heavy that the momentum of said mass will substantially absorb recoil resulting from discharge of the projectile cartridge.

2. The combination described in claim 1, including means to move the sear means to holding position with respect to the dynamic mass upon recoil of the latter.

3. The combination described in claim 1 including frangible means on the projectile to engage the projectile supporting means of the gun.

4. The combination described in claim 1 including a magazine positioned above the projectile supporting means, and means operated upon rearward movement of the dynamic mass to feed projectiles from said magazine to the projectile supporting means.

5. In a gun for projecting a projectile, which projectile is provided with an axial bore open at its rearward end with a propellant cartridge including a rearwardly movable obturating portion positioned in the bore in advance of said rearward end of the projectile, a casing, a heavy dynamic mass including a forwardly extending firing pin element movable therewith, said mass being reciprocable in said casing, means for driving said mass toward the forward end of said casing, sear means for holding said mass against the action of said driving means, trigger means to operate said sear means to release position, projectile supporting means beyond the forward end of said casing adapted to hold the projectile substantially stationary during the forward travel of said mass and until the propellant cartridge is discharged, said firing pin element having sufficient length forwardly of said mass that when

said mass is moved forwardly the forward end of said element will extend past the forward end of said casing and into the projectile recess so as to engage the projectile propellant cartridge, whereby discharge of the propellant cartridge will result in creation of explosive gases adapted to be primarily effective in the projectile recess so as to drive the obturating portion of the cartridge against said firing pin element, said mass and the driving means therefor being sufficiently heavy that the momentum of said mass will substantially absorb the recoil resulting from discharge of the projectile cartridge.

6. The combination described in claim 5, including means to move the sear means to holding position with respect to the dynamic mass upon recoil of the latter.

7. A gun of the character described in claim 5 including a magazine positioned above the projectile supporting means, and means operated upon rearward movement of the dynamic mass to feed projectiles from said magazine to the projectile supporting means.

8. The combination described in claim 1, including means to move said dynamic mass to a position for holding engagement by said sear means and independently of recoil action.

9. The combination described in claim 5, including means to move said dynamic mass to a position for holding engagement by said sear means and independently of recoil action.

10. The combination described in claim 1, including a tube element carried by said casing and engaged by said dynamic mass when the latter is in forward position, said tube element being movable rearwardly of the casing to move the dynamic mass into position to be held by said sear means.

11. The combination described in claim 5, including a tube element carried by said casing and engaged by said dynamic mass when the latter is in forward position, said tube element being movable rearwardly of the casing to move the dynamic mass into position to be held by said sear means.

LATHAM VALENTINE STEWART BLACKER.
